United States Patent Office

Des. 193,018
Patented June 12, 1962

193,018

SPOON OR SIMILAR ARTICLE

Andrew C. Larsen, 2438 Logan Ave. N.,
Minneapolis, Minn.

Filed Apr. 7, 1961, Ser. No. 64,649

Term of patent 7 years

(Cl. D44—29)

FIG. 1 is the top plan view of a Spoon or Similar Article, showing my new design;

FIG. 2 is a side elevational view;

FIG. 3 is an end elevational view on line 3—3 of FIG. 2; and

FIG. 4 is a bottom plan view.

The essential features of this design are shown in full lines.

I claim:

The ornamental design for a spoon or similar article, as shown and described.
